UNITED STATES PATENT OFFICE

167,419

CHAIR

Matvey F. Pechnikoff, Los Angeles, Calif.

Application June 11, 1951, Serial No. 15,490

Term of patent 7 years

(Cl. D15—8)

To all whom it may concern:

Be it known that I, Matvey F. Pechnikoff, a citizen of the United States, residing in Los Angeles, California, have invented a new, original, and ornamental Design for a Chair, of which the following is a specification, reference being had to the accompanying drawing, forming a part hereof.

Fig. 1 is a perspective view of a chair showing my new design;

Fig. 2 is a top plan view of the chair illustrated in Fig. 1;

Fig. 3 is a side elevational view;

Fig. 4 is a front elevational view.

I claim:

The ornamental design for a chair, as shown.
MATVEY F. PECHNIKOFF.
